UNITED STATES PATENT OFFICE.

EPHRAIM MORRIS, OF NEW YORK, N. Y.

METHOD OF KEEPING THE VALVES OF OSCILLATING ENGINES UPON THEIR SEATS.

Specification of Letters Patent No. 8,706, dated February 3, 1852.

To all whom it may concern:

Be it known that I, EPHRAIM MORRIS, of the city, county, and State of New York, machinist, have invented, made, and applied to use certain new and useful Improvements in Oscillating Steam-Engines; and I hereby declare that the construction, operation, and effects of the said improvements are fully and substantially set forth and shown in the following description and in the drawing annexed to and making part of this my specification thereof, wherein—

Figure 1, is a plan, Fig. 2 is a side elevation, on the side A, of Fig. 1, Fig. 3, is a cross section on the line B, C, showing the induction steam passages and Fig. 4, is a longitudinal section at the line D, of Fig. 1, showing the internal form of the steam passages on each side, and the mode of fitting the parts that form the valve ways for the steam in the induction and eduction.

The like marks of reference denote the corresponding parts in all the figures.

E, is the bed frame fitted with a pair of standards *a*, *a*, on each side; *b*, *b*, are journal boxes carrying the trunnions *c*, *c*, of the oscillating steam cylinder F, which is fitted with heads, piston, piston rod and stuffing box and side steam ways *d*, *d*, to the steam ports, all as now usually made. Over the trunnions on each side the steam ways are raised to form a segment curve *e*, concentric with the trunnions and fitting under the curve *e*¹, of each leg of the steam chest G, the steam ways in which are shown by dotted lines in Fig. 1, and in section in Figs. 3 and 4, the induction ways being denoted by 3, 3, are connected together by an opening through the center of the steam chest 40 and to the induction pipe *h*; the eduction ways 4, 4, are connected by a semicircular opening surrounding the induction pipe with the eduction pipe *i*; the valve seats *e*, *e*, have steam ways 1 and 2, connecting with the steam ways *d*. Each end *f*, *f*, of the steam chest G, is made to fit between the upper ends of the standards *a*, *a*, and is made hollow as shown in Fig. 3, to admit steam to act under pressure plugs 5, 5, at each end which take under caps *g*, *g*, secured and adjusted by screws 6, 6. At *k*, is the connection of the piston rod to the crank *l*, on the shaft 7.

The operation is as follows; the steam enters by the steam ways 2, and 3, Fig. 4,

into the steam ways on each side of the cylinder, and acts on the piston the steam passing in the direction of the arrow 8, see Fig. 4, and the exhaust passing off in the direction of the arrow 9, by the ports 1 and 4, the motion of the cylinder as it oscillates by the rotation of the crank causing the valve seat *e*, to move under the valve *e*¹, allowing the steam to enter and exhaust as required; the arrangement of the parts and their operation being the same as usual where the ways are through the trunnions.

The ordinary steam chests used in oscillating steam engines are usually secured down by screws and worked with the pressure they are intended for, but if less pressure of steam is used the valve grinds and wears unnecessarily and when greater pressure is put on, the parts expand and the steam chest being secured rigidly in place very often causes a leak between the valves and also the excess of pressure tends to lift the steam chest. To remedy this the plugs 5, 5, are introduced and fitted to slide steam tight in their places immediately under the caps *g*, *g*, so that the steam pressing under the plugs raises them against the caps which being secured causes a reaction of the steam on the lower part of the steam ways and chest that forces the chest bodily downward upon the convex valve seat *e*, *e*, on each side so that the higher the pressure of the steam the more effectively the steam chest is depressed on to the convex segments and the area of each plug being a little more than equal to the area of the steam ways on one side there is a pressure downward always greater than the pressure tending to separate the steam chest from the valve seat and consequently the valve and seat are kept tight under all pressures without unnecessary friction and wear and the pressure is adjusted by the steam itself.

Oscillating steam cylinders have been made that admit and exhaust the steam through the trunnions, and others have been made that admit and exhaust the steam in the upper or lower part on the central line of the cylinder, and some have been made to admit and exhaust at the sides but I do not know of any oscillating engines in which the steam is admitted or exhausted at the sides in combination with a means of making the pressure of the steam act to keep the steam chest down on the working parts

of the steam ways so as to resist the lifting caused by the unbalanced pressure of the steam in the steam chest,—therefore

What I desire to secure by Letters Patent is—

I claim the pressure plugs 5, or their equivalents acting against the caps g , or their equivalents in combination with the steam chest G, valve e^1 , and valve seat or 10 seats e , vibrating with the steam cylinder; said plugs 5, operating to keep the valve or

valves onto the seat or seats of the same as described and shown.

In witness whereof I have hereunto set my signature this twenty-sixth day of December one thousand eight hundred and fifty-one.

EPHM. MORRIS.
